AIRCRAFT GROUND SUPPORT CART

Joseph T. Abdo, Rolling Hills, Calif., assignor to
The Rucker Company, a corporation

Filed Oct. 22, 1968, Ser. No. 14,111

Term of patent 14 years

Int. Cl. D12—13

U.S. Cl. D14—3

FIG. 3

FIG. 2

FIG. 1

FIG. 6

FIG. 5

FIG. 4

FIGURE 1 is an isometric view of an aircraft ground support cart showing my new design;

FIGURE 2 is a front end elevation of the article of FIGURE 1;

FIGURE 3 is an elevation of one side of the article of FIGURE 1;

FIGURE 4 is a rear end elevation of the article of FIGURE 1;

FIGURE 5 is an elevation of the other side of the article of FIGURE 1; and

FIGURE 6 is a top plan view of the article of FIGURE 1.

I claim:

The ornamental design for an aircraft ground support cart, as shown.
